UNITED STATES PATENT OFFICE.

FRANK S. CLARKSON, OF BALTIMORE, MARYLAND.

SASH-CORD GUIDE.

SPECIFICATION forming part of Letters Patent No. 225,969, dated March 30, 1880.

Application filed December 23, 1879.

To all whom it may concern:

Be it known that I, FRANK S. CLARKSON, of Baltimore city, State of Maryland, have invented certain new and useful Improvements 5 in Sash-Cord Guides; and I hereby declare the same to be fully, clearly, and exactly described as follows, reference being had to the accompanying drawings, in which—

Figure 1 is a perspective view of the device; 10 Fig. 2, a plan view of the yoke or holder.

The object of my invention is to furnish a sash-cord guide which shall be far cheaper in construction than those in use, while, as incidental to its peculiar construction, increased 15 facility is afforded for inserting it in the window-frame; and it consists, essentially, in the substitution for the usual casing of a simple yoke in which the sheave is pivoted, as hereinafter set forth.

20 In the accompanying drawings, A is the sheave, having a pivot-pin, C, as usual. B is a yoke crossing the sheave at b sufficiently close to retain the rope in the groove, while admitting of the free revolution of the sheave. 25 This yoke is provided with segmental flanges c e, which may be perforated for securing-screws; but by preference the sides of the yoke are somewhat roughened or barbed, so that when driven into the window-frame the 30 device is securely retained.

The sides of the yoke are curved in the arc

of a circle about its longitudinal axis, and each is provided with a slot, a, for the pivot-pin C.

To insert the device in a window-frame, a hole is bored of the size of the yoke B by 35 means of a bit, which has, at the proper distance from its point, a second cutter, which sinks a recess for the flange c, as will be readily understood. A mortise is made for the sheave, crossing the hole for the yoke, and the 40 frame is ready for the insertion of the device. This is accomplished by simply inserting the sheave in the yoke and driving the latter into the hole until the flange c is flush with the window-frame.

45 The advantages of the device over the usual sash-cord guide are evident. It does away with the cumbrous casing, which had to be carefully fitted into a mortise in the frame, and substitutes for it a light and simple yoke separable from the sheave and of such construction as to admit of its insertion with the minimum expenditure of time and labor.

50 What I claim is—

A sash-cord guide consisting of a sheave 55 pivoted within or upon a yoke which crosses the rear side of the sheave, and whose exterior walls are cylindrical, as set forth.

FRANK S. CLARKSON.
